UNITED STATES PATENT OFFICE

CLARENCE F. COVEY, OF PITTSBURGH, PENNSYLVANIA, ASSIGNOR TO THE MC AULEY AUTOMATIC TRAP COMPANY, OF PITTSBURGH, PENNSYLVANIA, A CORPORATION OF DELAWARE

LUMINOUS TUBE SIGN

Application filed October 18, 1929. Serial No. 400,528.

This invention relates to luminous tube signs, and particularly to the mounting of such signs. The invention constitutes an improvement on the invention of Werner I. Staaf, Jr., disclosed in application Serial No. 348,897, filed March 21, 1929.

Luminous tube signs, such, for instance, as the well-known Neon signs, are comprised of glass tubing bent to the desired contour and having a rarefied gas content therein with an electrode at each end of the tube. A relatively high voltage is impressed on the electrodes, necessitating that the tubes be mounted in spaced relation to the panel or supporting structure on which they are carried.

The tube is bent in such a manner that different portions of the sign are at different elevations from the base or supporting structure. This necessitates the use of supporting means of different heights on different portions of the sign.

In the application of Werner I. Staaf there is disclosed an elevation post in the form of a glass stem having a saddle thereon providing a seat for the tube, and the tube is secured to the saddle by means of wires. The stem of the tube is provided with a projection that passes between convolutions of a helical spring. By turning the glass post relatively to the spring, it will screw up or down to vary the height of the post. Such an arrangement, while providing effective insulation, permits the use of a single size of post instead of a plurality of posts of different heights. The spring has the additional advantage of providing resilience so that breakage of the sign from shock and mechanical strain is materially reduced. Tube manufacturers have found that by the use of such a post the breakage of the tubes of the signs during the manufacture thereof is very considerably reduced.

The Board of Fire Insurance Underwriters has required that a certain minimum distance be maintained between the sign and any metal part of the elevation post which is in contact with the base or supporting structure on which the sign is carried. The structure shown in the Staaf application is open to the objection that the glass post can be

screwed down into the spring until the underside of the saddle at the top of the post contacts directly with the metal spring. In this position, the minimum insulation between the tube and the metal is not maintained. This same objection exists in all other adjustable elevation posts now available.

According to the present invention there is provided an elevation post wherein the minimum space between the metal and the tube can always be maintained without interfering materially with the adjustability of the post. The invention, furthermore, provides a novel method and means of securing the tube to the top of the post, and provides a saddle on the post of such construction that a tube has a two-contact support on the post.

The invention may be readily understood by reference to the drawings in which

Figure 1 is a side elevation of a portion of a luminous tube sign showing the glass post screwed into the spring to the maximum extent;

Figure 2 is a similar view showing the glass post lifted or extended to a height beyond that shown in Figure 1;

Figure 3 is a perspective view of the elevation post;

Figure 4 is a top plan view showing the first step in wiring or tying the luminous tube to the post; and

Figure 5 is a side elevation showing the completed step of tying the tube to the post.

In the drawings, 2 designates a luminous tube sign. It is supported above a base or supporting structure 3 by means of elevation posts. The elevation post comprises a glass stem 4 having an elongated head or saddle portion 5 at the top thereof. In the top of the saddle is a V-shaped recess 6 into which the tube 2 sets. By reason of the slope of the inclined sides of the recess 6, the tube contacts with the saddle at two points, so that the saddle provides a firm support, and tends to assist in holding the tube against sidewise movement. Because of the V-shape of the grooves, the post is adaptable for use with all the different diameters of tubes commonly employed in the industry, and is

equally satisfactory with any diameter. Heretofore elevation posts, as shown in the Staaf application, have had a rounded seat so that the tube, the curvature of which did not conform to the curvature of the seat, made contact with the seat at only one point, and did not have a firm contact with the post.

The stem 4, which is preferably made of solid glass, has a transversely elongated elliptical projection 6 thereon. This projection has flat top and bottom surfaces, and is entered between the convolutions of the supporting spring 7. The spring 7 is held firmly on the base 3 by means of a screw 8 which passes through the eye 9 at one end of the wire which forms the spring.

The elongated sides of the projection 6, extending between the convolutions of the helical spring 7, tend to force the adjacent convolutions of the spring apart. This increases the binding effect of the spring on the post, holding the glass post against relative movement with respect to the spring. This binding action is effective even though the diameter of the post 4 is materially less than the inside diameter of the spring. The projection, of course, acts as a thread for causing the post to move up or down with respect to the spring when the post is rotated relatively to the spring. The binding effect of the elongated projection 6 is just as great as if a complete thread were actually formed on the post. The elliptical ends of the projection serve to decrease the resistance to the turning of the post with respect to the spring, so that the sign builder can easily and quickly adjust the post to the proper height. Where a small projection was used, the projection was found to frequently bind between the convolutions of the spring and the turning of the post with respect to the spring could only be accomplished with difficulty.

Projecting down from the underside of the head of the saddle 5 on one side of the stem is a rib 10. This rib is adapted to contact with the upper end of the spring when the post is screwed down so as to limit the adjustability of the post downward. This is clearly shown in Figure 1, where the end portion 7a of the spring is in contact with the rib 10, preventing further rotation of the post with reference to the spring in a direction to move the post downward. By reason of the provision of the rib 10, the distance between the top of the spring and the luminous tube is constant, and it is impossible for the manufacturer of the sign to violate the provision of the underwriters, either intentionally or unintentionally. At the same time, should a shorter post be desired than the post shown in Figure 1, the sign builder can very easily shorten the post by merely clipping off the upper part of the spring.

For instance, if the sign builder were to clip off the portion of the spring above the dotted line AA, he could screw the post down into the spring farther until the end of the spring can come in contact with the rib 10. At the same time, the minimum distance between the top of the spring and the luminous tube would be maintained.

In Figures 1 and 2 I have shown the tube 2 as being secured to the post by means of two separate wires passing around the tube and under the saddle, these wires being designated 11. For the purpose of preventing the wires from slipping out from under the saddle, the under portion of the saddle has a slight rib 12 at each end thereof.

In order to do away with two separate tie wires, as shown in Figures 1 and 2, I form the tie wire into a loop of hairpin shape, as shown in Figure 4. The loop is then inserted under the saddle, one leg of the loop passing to each side of the glass post. The looped wire is designated 13 in Figure 4. The closed end of the loop, and the projecting ends of the two legs of the loop are then bent up over the top of the tube, as shown in Figure 5, and the closed end of the loop and the free ends thereof are then twisted together, as indicated at 13a in Figure 5.

This manner of tying the tube to the top of the elevation post is just as satisfactory as the use of two separate wires, and the single loop can be applied just as quickly as either one of the tie wires 11 in the arrangement shown in Figures 1 and 2. This method of securing the tube on the post therefore saves the sign builder considerable time. Some signs may have several hundred elevation posts, and this method of securing the tube to the post is therefore of considerable advantage to the sign builder.

The elevation post constructed in accordance with the present invention is adjustable within the limits required in commercial practice, and still maintains a construction in which the minimum of insulation between the tube and the post is always provided. Likewise, the invention assures of the proper required spacing between the tie wires which pass around the tube, and the metal spring. It provides a construction which is resilient and therefore relieves the tube of strain and, in effect, provides a cushioned support for the tube. At the same time, due to the tight bearing of the convolutions of the spring against the upper and lower faces of the projection 6, there is no looseness between the glass post and the spring. The invention, moreover, provides a quick method of securing the tube on the seat, and the seat of the tube is one in which the tube has a two-point contact, so that it is held firmly against the sidewise movement relatively to the elevation post.

While I have shown a preferred embodi-

ment of my invention, it will be understood that various changes and modifications may be made therein within the contemplation of my invention and under the scope of the following claims.

5 I claim:

1. In an elevation post for luminous tube signs, a post member of insulating material having a stem with a seat at the top thereof, a helical spring into which the stem projects, a projection on the stem entered between adjacent convolutions of the spring, and a vertically extending rib on the stem adapted to contact with the end of the spring and limit relative movement between the post member and the spring.
- 10 2. In a luminous tube sign, an elevation post of insulating material, a helical spring into which one end of the post projects, and a transversely elongated elliptical projection on the post projecting between the convolutions of the spring.
- 15 3. An elevation post for luminous tube signs comprising a stem of insulating material having an elongated head at one end thereof and having the other end thereof received within a helical spring, a projection on the stem passing between convolutions of the spring, and a rib on the stem extending partly down the stem toward said projection and forming an obstruction to limit the turning movement of the post with respect to the spring.

20 In testimony whereof I have hereunto set
35 my hand.
